DESIGN FOR A RADIO LOUD SPEAKER HOUSING OR SIMILAR ARTICLE

Arthur F. Adams and Nathaniel S. Barger,
Chicago, Ill.

Application October 15, 1945, Serial No. 122,850

Term of patent 3½ years

(Cl. D26—14)

To all whom it may concern:

Be it known that we, Arthur F. Adams and Nathaniel S. Barger, both citizens of the United States, residing at Chicago, in the county of Cook and State of Illinois, have invented a new, original, and ornamental Design for a Radio Loud Speaker Housing or Similar Article, of which the following is a specification, references being had to the accompanying drawing, forming part thereof.

Figure 1 is a side elevational view of the radio loud speaker housing or similar article, showing our new design;

Fig. 2 is a similar view looking at the head from a position which is 90° to one side; and

Fig. 3 is a top plan view thereof.

The dotted lines shown in Figures 1 and 2 of the drawing are for illustrative purposes only.

We claim:

The ornamental design for a radio loud speaker housing or similar article, as shown and described.

ARTHUR F. ADAMS,
NATHANIEL S. BARGER.
